Leo F. Howard, Birmingham, Mich., assignor to Metal & Thermit Corporation, New York, N.Y., a corporation of New Jersey

Application August 26, 1957, Serial No. 680,070

5 Claims. (Cl. 204—213)

This invention relates to electroplating barrels and particularly to improved means for removing the work therefrom. The embodiment of the invention illustrated in the drawings is shown in connection with an electroplating barrel of a type used in chromium plating.

The invention is illustrated in the accompanying drawings, wherein

Fig. 1 is a plan view of an electroplating barrel;
Fig. 2 is a side elevation partly in section of said barrel;
Fig. 3 is a section through 3—3 of Fig. 2;

Fig. 4 is a section through 4—4 of Fig. 5 and shows one part of the wall of the barrel with the work removing blade mounted on the barrel wall;

Fig. 5 is an end view (see arrow 5 in Fig. 4) of that part of the barrel wall which is illustrated in Fig. 4 with part of the wall cut away to show the work removing blade and work;

Fig. 6 is a section through 6—6 of Fig. 4 but with the work removing blade raised to inoperative position; and

Fig. 7 is a diagrammatic view showing some of the parts from the open end of the barrel and their direction of rotation.

Referring to said drawings, only the main features of the electroplating barrel will be referred to because this invention has to do with the means for removing work from the barrel and not the over-all construction of the barrel itself.

Looking at Fig. 2, F shows a suitable supporting framework upon which is positioned a tank T. Rotatably mounted above the tank is the rotatable barrel B which is positioned on the framework and tank so that the lower part thereof is immersed in the solution of the tank when the solution is at normal level. Barrel B is supported on and driven by a shaft S. Motor M through a suitable reduction gear R drives the shaft S. The barrel B is open at the left end, as viewed in Figs. 1 and 2. The right end or the right end wall serves to support the barrel on the shaft S. The barrel is made of metal and each end wall has lips L which on the left side, as viewed in these figures, form the opening to the interior of the barrel. The tank is equipped with the usual temperature control coil C, circulator P and exhaust.

The anode for the bath is shown at A. Current is fed to this anode by the cable 1; The body of the barrel acts as the cathode and it is electrically connected to the circuit through means of the brushes shown at B' (Fig. 1).

This invention particularly has to do with means for removing work from the barrel. Such work is shown at W (Figs. 2, 3, 5 and 6). Normally this work is tumbled around on the bottom of the barrel B in the solution contained in the tank T. The inside of the cylindrical barrel wall is metal and makes contact with the work. The work removal means comprises a blade 10, pivoted on the narrow end walls or lips L, as shown in Figs. 3—7. The pivotal axis of the blade is parallel to the longitudinal axis of the barrel and spaced from the outer cylindrical

2

wall of the barrel by a distance substantially equal to the width of the lips or walls L, as shown in the above-mentioned figures. Blade 10 is supported on suitable pivot pins, one of which is shown at 14 on the left side of Fig. 4, and the other at 15 on the right side of the same figure. A wing nut 17 permits frictional adjustment of blade 10 so that it will stay in the position it is put in by the operator.

A suitable operating handle 16 is attached to blade 10 so that the blade may be turned about its pivot axis between the position shown in Fig. 5 and position shown in Fig. 6. When the blade 10 is in the position shown in Figs. 6 and 7, the outer or free edge thereof is spaced a substantial distance from the inner cylindrical wall of the barrel B and the work is free to move under the blade 10, as it is tumbled about in the bottom of the barrel. The direction of rotation of the barrel in relation to the blade is indicated in Figs. 3, 5, 6 and 7. As viewed from the open end of the barrel, the rotation is counter-clockwise.

A suitable screen or tray 20 is supported on horizontal tracks 21, 22 which extend from the outside of the barrel through the open end thereof into the interior of the barrel above the anode A, as shown in Figs. 1—3. This tray may be moved in and out of the barrel on the tracks 21 and 22 and may also be arranged so as to be lifted off the tracks, as shown in the dot-dash position of Fig. 2. It is also contemplated, although not illustrated, that tracks 21 and 22 may be constructed so that they can be withdrawn from barrel B when tray 20 is not in use.

After the work has been subjected to the electroplating process for a sufficient length of time, and it is desired to remove it from the barrel, it is only necessary to move the blade 10 from the position shown in Fig. 6 to the position shown in Fig. 5. As the blade comes along toward the bottom of its path of travel, it will engage the work between its advancing face and the cylindrical wall of the barrel, as shown in Fig. 5; and then carry the work upwardly to the position shown in Fig. 3 where the work will spill off the blade on to the tray 20, as illustrated in Fig. 3. When this has been accomplished, it is only necessary to pull out the tray to the position shown in Fig. 2 and remove the work either with or without the tray. The blade can then be returned to the position shown in Fig. 6 where it is inoperative and other work may be introduced for electroplating.

With this device work can be removed from the barrel without stopping rotation thereof. It is only necessary for the operator to move the blade 10 through an arc of about 45° to bring it to its operative position and upon rotation of the barrel through an arc of a little more than 180° the work will be deposited on the tray 20 for removal.

The blade must be electronically isolated so that it does not conduct current and interfere with the plating operation. This may be accomplished by using a blade of a non-conducting material, e.g. a plastic, by coating the blade with a non-conducting material, by insulating the blade from the barrel at its mountings, etc.

With the present construction the blade does not "blanket" the inner surface of the barrel so as to impede electroplating deposition; the work is always in contact with the inner surface of the barrel when the blade is in operative position. Both the blade 10 and the anode A may be moved into a position where they will not be immersed in the solution when work is discontinued.

The construction is simple and rugged and it lends itself to incorporation in a commercial type of electroplating barrel.

What is claimed is:

1. In barrel plating device, especially applicable for chromium plating from the chromic acid type solution, comprising a tank adapted to hold the plating solution at a predetermined solution level therein, a rotatable metallic barrel adapted to be partly immersed in said solution and with which work articles therein may make electrical contact having at least one end wall with a large central opening through which objects may extend and be introduced into or removed from the barrel without meeting obstruction when the barrel is rotated, the combination of a work-removing apparatus comprising a work-removing blade extending longitudinally of said barrel with its longitudinal axis parallel to the axis of said barrel, pivot bearings for said blade in the end walls of said barrel located nearer the peripheral wall of the barrel than the axis thereof and adapted to permit said blade to be pivoted around the axis of said pivotal bearings so as to bring the free edge of said blade into contact with the inner peripheral wall of said barrel to entrap work articles between said blade and rotating barrel wall or alternatively permit said free edge of said blade to be moved away from said inner peripheral surface of said barrel to permit work articles to move freely along the inner wall of said barrel and a removable work-receiving tray in said barrel.

2. In barrel plating device, especially applicable for chromium plating from the chromic acid type solution, comprising a tank adapted to hold the plating solution at a predetermined solution level therein, a rotatable metallic barrel adapted to be partly immersed in said solution and with which work articles therein may make electrical contact having at least one end wall with a large central opening through which objects may extend and be introduced into or removed from the barrel without meeting obstruction when the barrel is rotated, the combination of a work-removing apparatus comprising a rectangular work-removing blade extending longitudinally of said barrel with its longitudinal axis parallel to the axis of said barrel, pivot bearings for said blade in the end walls of said barrel adapted to permit said blade to be pivoted around the axis of said pivotal bearings so as to bring the free edge of said blade into contact with the inner peripheral wall of said barrel to entrap work articles between said blade and rotating barrel wall or alternatively permit said free edge of said blade to be moved away from said inner peripheral surface of said barrel to permit work articles to move freely along the inner wall of said barrel, and work-receiving means adapted to be positioned in said barrel under said blade when said blade is near the top of its path of rotation, said means adapted to receive work trapped between said blade and the inner peripheral wall of said barrel as said blade moves across the top of its path of rotation and said work articles fall from the entrapment space between said blade and barrel wall.

3. In barrel plating device, especially applicable for chromium plating from the chromic acid type solution, comprising a tank adapted to hold the plating solution at a predetermined solution level therein, a rotatable metallic barrel adapted to be partly immersed in said solution and with which work articles therein may make electrical contact having at least one end wall with a large central opening through which objects may extend and be introduced into or removed from the barrel without meeting obstruction when the barrel is rotated, the combination of a work-removing apparatus comprising a work-removing blade extending longitudinally of said barrel, pivot bearings for said blade in the end walls of said barrel and adapted to permit said blade to be pivoted around the axis of said pivotal bearings so as to bring the free edge of said blade into contact with the inner peripheral wall of said barrel to entrap work articles between said blade and rotating barrel wall or alternatively permit said free edge of said blade to be

10 moved away from said inner peripheral surface of said barrel to permit work articles to move freely along the inner wall of said barrel and work-receiving means adapted to be positioned in said barrel under said blade when said blade is near the top of its path of rotation, said means adapted to receive work trapped between said blade and the inner peripheral wall of said barrel as said blade moves across the top of its path of rotation and said work articles fall from the entrapment space between said blade and barrel wall.

15 4. In barrel plating device, especially applicable for chromium plating from the chromic acid type solution, comprising a tank adapted to hold the plating solution at a predetermined solution level therein, a rotatable metallic barrel adapted to be partly immersed in said solution and with which work articles therein may make electrical contact having at least one end wall with a large central opening through which objects may extend and be introduced into or removed from the barrel without meeting obstruction when the barrel is rotated, the combination of a work-removing apparatus comprising a work-removing blade extending longitudinally of said barrel with its longitudinal axis parallel to the axis of said barrel, pivot bearings for said blade in the end walls of said barrel located nearer the peripheral wall of the barrel than the axis thereof and adapted to permit said blade to be pivoted around the axis of said pivotal bearings so as to bring the free edge of said blade into contact with the inner peripheral wall of said barrel to entrap work articles between said blade and rotating barrel wall or alternatively permit said free edge of said blade to be moved away from said inner peripheral surface of said barrel to permit work articles to move freely along the inner wall of said barrel, and work-receiving means adapted to be positioned in said barrel under said blade when said blade is near the top of its path of rotation, said means adapted to receive work trapped between said blade and the inner peripheral wall of said barrel as said blade moves across the top of its path of rotation and said work articles fall from the entrapment space between said blade and barrel wall.

20 5. In barrel plating device, especially applicable for chromium plating from the chromic acid type solution, comprising a tank adapted to hold the plating solution at a predetermined solution level therein, a rotatable metallic barrel adapted to be partly immersed in said solution and with which work articles therein may make electrical contact having at least one end wall with a large central opening through which objects may extend and be introduced into or removed from the barrel without meeting obstruction when the barrel is rotated, the combination of a work-removing apparatus comprising a rectangular work-removing blade extending longitudinally of said barrel with its longitudinal axis parallel to the axis of said barrel, pivot bearings for said blade in the end walls of said barrel located nearer the peripheral wall of the barrel than the axis thereof and adapted to permit said blade to be pivoted around the axis of said pivotal bearings so as to bring the free edge of said blade into contact with the inner peripheral wall of said barrel to entrap work articles between said blade and rotating barrel wall or alternatively permit said free edge of said blade to be moved away from said inner peripheral surface of said barrel to permit work articles to move freely along the inner wall of said barrel, and work-receiving means adapted to be positioned in said barrel under said blade when said blade is near the top of its path of rotation, said means adapted to receive work trapped between said blade and the inner peripheral wall of said barrel as said blade moves across the top of its path of rotation and said work articles fall from the entrapment space between said blade and barrel wall.
